TOBACCO STRIPPING MACHINE

Filed March 5, 1928

Inventor,
Morris Godfrey Philip Phillips,
By his attorney, Arnold J. Penney

UNITED STATES PATENT OFFICE

MORRIS GODFREY PHILIP PHILLIPS, OF LONDON, ENGLAND

TOBACCO-STRIPPING MACHINE

Application filed March 5, 1928, Serial No. 259,259, and in Great Britain January 18, 1928.

This invention relates to machines for stripping tobacco leaves, and it refers particularly to machines of the type in which a stripping device is employed provided with teeth or serrations each receiving the stem of a leaf, means being provided for simultaneously drawing the stems lengthwise through the stripping device.

The present invention has for its object to provide means whereby when desired to feed the leaves directly from a stationary belt or table the extent to which the stems project through the stripping device may be automatically controlled, and the stems aligned prior to the stripping operation.

By means of the present invention moreover any stems which may adhere to the gripper members after the stripping operation has been effected are automatically ejected.

According to the present invention there is provided upon the gripper by which the stems are drawn through the stripper a body designed to act as a stop or fence, which body is disposed behind the stem engaging elements of the gripper, so that as the gripper advances said body contacts with the extreme ends of the stems and effects the alignment.

In order that the invention may be better understood drawings are appended in which:—

Fig. 1 is a side view of a machine embodying the present invention.

Fig. 2 is a sectional view to a larger scale showing the parts in position to grip the stems.

Fig. 3 is a similar view with the parts in the gripping position.

Fig. 4 is a detail view of the stem aligning mechanism.

Fig. 5 is a fragmentary perspective view of the stripping elements.

Referring to the appended drawings, in which only such parts of the machine as are essential to the proper understanding of the invention are shown and described, 1 indicates the frame of the machine. 2 indicates the support upon which the leaves are placed with their stems projecting beyond the inner edge thereof, said leaves being roughly aligned thereon.

4 indicates the stripper which is in the form of a bar or plate having teeth or serrations as previously stated, and as illustrated in the fragmentary perspective view, Fig. 5, said plate being carried by a bar 5, supported at its ends by levers such as 6. 7 indicates a member cooperating with the serrated stripper plate 4, said member being supported by levers such as 8. The levers 8 are pivotally mounted at 8^a upon reciprocating carriages such as 9, whilst the levers 6 are pivotally mounted upon the carriages 9 at 6^a, links 10 connecting the inner ends of levers 6 with levers 8 in a manner such that the movement of the levers 6 in one direction will impart movement in an opposite direction to the levers 8, or in other words, will cause the stripper to open or close. The movement of the levers 6 and 8 is effected by means of rollers such as 11 carried by arms such as 6^b 70 upon the levers 6, said rollers engaging suitable cams adapted to secure the desired operation of the said levers.

The gripping elements indicated by 12 and 13 are carried by systems of levers, indicated generally by α , α^1 supported by carriage 15, the arrangement and operation of the levers being, as already described, in connection with the stripper.

Secured at their ends to the levers α , α^1 are 80 bars or rods 16 disposed upon the inner side of the gripping elements over which passes an endless body a conveniently formed of fabric, which body also passes over a third rod 17, the ends of which are secured to one end of springs 18, the opposite ends of said springs being connected to a fourth rod or bar 19 secured at its ends to the carriage 15.

With the gripper in the open position, as shown in Fig. 2, the body a is caused to assume a condition such that it presents a triangular shaped cross sectional outline of which the base is vertical, and forms a stop or fence which, contacting with the inner ends of the stems of the leaves, will effect 85 their alignment and so insure that the minimum length of stem will project beyond the gripping elements and consequently that the maximum stripping effect is secured.

When in the closed position the parts will 100

be substantially in the condition shown in Fig. 3, the springs 18 drawing up the slack of the body α , which would otherwise be present when the gripping elements come together.

5. Disposed at the rear of the frame 1 and running transversely thereof is a shaft 20, upon each end of which is mounted a flywheel such as 21, which is provided near the periphery with a pin 22 upon which is mounted one end of a link 23, the other end of which link is connected to the carriage 9, whereby when motion is imparted from a main drive shaft indicated by 24 to the shaft 20 a reciprocal motion is imparted to the carriage 9.

10. Disposed upon each side of the frame 1 and pivotally connected at their lower ends thereto are levers such as 25 which are connected midway of their length by links such as 26 to the carriage 9, and are at their upper ends connected by means of links such as 27 to the carriage 15, the arrangement being such that when a reciprocal motion is imparted to the carriage 9 in the manner above described a 15 reciprocal motion of greater amplitude is simultaneously imparted to the carriage 15.

15. In operation, the tobacco leaves are placed upon the feed belt 2 with the butt ends projecting therebeyond. As explained heretofore, as the gripper and stripper members move into operative position, the jaws of both gripper and stripper are open. The sheet α , in this open position of the gripper, as shown in Fig. 2, provides a wall or fence 20 which comes into contact with the ends of the stems, and effects the desired alignment.

20. The jaws of the gripper then close, it being noted that the aligning action will take place with the ends of the stems between the open jaws of the gripper. The stripper closes, and both members move backward, the stripping operation thus being effected.

25. At the end of the stripping operation, the gripper opens. Now, should any stalks adhere to the jaws of the gripper, such stalks would be rubbed or pushed against the relatively stationary surface provided by the sheet α . It will be noted that the jaws of the gripper move relative to the surface of the wall α directly behind it, thus the aligning wall α also functions as a means to automatically remove any stems or stalks that may adhere to either of the gripper jaws.

Claims:

30. 1. In a tobacco stripping machine a support for the leaves, means for stripping the leaves, gripping means engaging and drawing the leaves through said stripper and means abutting the ends of the stems when in the gripper for limiting the extent to which the leaves project through said gripper.

35. 2. In a tobacco stripping machine a support for the leaves, a stripper comprising a stripping element having serrations there-

in each adapted to engage a single stem and means for retaining the stems in said stripping element, a gripper engaging the stems and drawing them through the stripper and means upon the gripper designed to limit the extent to which the stems project through 70 said gripper.

3. In a tobacco stripping machine a support for the leaves, a stripper comprising a stripping element having serrations therein 75 each adapted to engage a single stem and means for retaining the stems in said stripping element, a gripper comprising two members movable to permit the passage of the stem between them and to grip same, a flexible body designed to limit the extent to which the stems project through said gripper.

4. In a tobacco stripping machine a support for the leaves, a stripper comprising a stripping element having serrations therein 80 each adapted to engage a single stem and means for retaining the stems in said stripping element, a gripper engaging the stems and drawing them through said stripper, said gripper comprising two members, levers supporting the ends of said members, means for operating said levers to move the gripping members to permit the passage of the stems between them and to grip same, a rod supported at its ends by the levers carrying one 85 gripper element, a second rod supported by the levers carrying the other gripper element, a third rod, springs acting upon said rod, a flexible body surrounding the three rods and acting to limit the extent to which the 90 stems project through said gripper.

5. In a tobacco stripping machine a support for the leaves, a stripper comprising a stripping element having serrations therein 95 each adapted to engage a single stem and means for retaining the stems in said stripping element, a gripper movable towards and away from said stripper and comprising two members, levers supporting the ends of said members; means for operating said levers to move the gripping members to permit the passage of a stem between them and to grip same, a rod supported at its ends by the levers carrying one gripper element, a second rod supported by the levers carrying the other gripper element, a third rod, springs acting upon said rod, a flexible body surrounding the three rods and acting to limit the extent to which the stems project through 100 said gripper.

6. In a tobacco stripping machine a support for the leaves, a stripper having a motion towards and away from said support and comprising a stripping element having serrations therein each adapted to engage a single stem, and means for retaining the stems in said stripping element, levers supporting the stripping and retaining elements, means for operating said levers to move the stripping and retaining elements to permit the 105 110 115 120 125 130 135 140 145 150

passage of the stems between them and to close thereon, a gripper movable towards and away from said stripper comprising two members, levers supporting the ends of said members, means for operating said levers to move the gripping members to permit the passage of a stem between them and to grip same, a rod supported at its ends by the levers carrying one gripper element, a second rod supported by the levers carrying the other gripper element, a third rod, springs acting upon said rod, a flexible body surrounding the three rods and acting to limit the extent to which the stems project through said gripper.

7. In a tobacco stripping machine, a support for leaves, means for stripping the leaves, means to grip and draw the leaves through said stripping means, means to align the ends of said leaves prior to their being gripped, motion of said gripping means relative to said aligning means removing leaf stems that adhere to the gripping means.

8. A tobacco stripping machine comprising a leaf carrier, means for stripping the leaves, means for gripping the stems of said leaves and drawing them through the stripping means, and means providing a relatively immovable surface to prevent stems from adhering to said gripping means when said stems are released.

9. In a machine, as defined in claim 2, said gripper including a pair of relatively movable members, and said limiting means being operative when said members are spaced apart.

In testimony whereof I have hereunto set my hand.

MORRIS GODFREY PHILIP PHILLIPS.
